(57) **CLAIM**

The ornamental design for a melon cutter, as shown and described.

DESCRIPTION

FIG. 1 is a first perspective view of a melon cutter showing my design;

FIG. 2 is a second perspective view thereof;

FIG. 3 is a front view thereof;

FIG. 4 is a side view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion of FIG. 1. The broken lines shown in the drawings depict portions of the melon cutter in which the design is embodied that form no part of the claimed design.
